COMBINATION SCREW AND RATCHET WRENCH FOR TANK CAR SAFETY VALVES

George J. Langmyhr, Sarnia, Ontario, Canada, assignor to Standard Oil Development Company, a corporation of Delaware

Application December 30, 1938,
Serial No. 248,446

3 Claims. (Cl. 81—61)

The present invention relates to a ratchet wrench assembly, and more particularly it relates to a ratchet wrench for breaking a threaded joint between cylindrical members.

The invention and its objects may be fully understood by reference to the following specification when read in connection with the accompanying drawings, in which:

Fig. 1 is a plan view of the wrench assembly, with parts broken away,

Fig. 2 is a side elevation of the assembly, with a section thereof removed along the line II—II of Fig. 1,

Fig. 3 is a perspective view showing the wrench assembly as applied to a tank car safety valve,

Fig. 4 is a sectional elevation showing a substituted element in the assembly,

Fig. 5 is a plan view of a sectional form of ratchet wheel collar,

Fig. 6 is a perspective view of a portion of the ratchet wheel collar shown in Fig. 5; and

Fig. 7 is a plan view of an alternate form of wrench body.

Although various adaptions of the invention may be made, in Figs. 1 to 4 inclusive, there is illustrated a form of the invention particularly suited for use in the removal of safety valves from the domes of tank cars or for use in any similar instance in which a protruding pipe end is to be manipulated.

In Figs. 5, 6 and 7 a showing is made of the alternate structural parts required to adapt the wrench principle to other uses.

Referring particularly to Figs. 1 to 4 inclusive, there is shown a wrench base having an enlarged annular head portion 1 and body portion 2. The body portion 2 carries oppositely-disposed, laterally-projecting ears 3 and 4 supporting bosses 5 and 6 respectively. Each of the bosses is drilled, with the passage thus formed extending through the ear from which it rises. A lever arm 7 having integrally formed yoke portions 8 and 9 at its ends is eccentrically mounted on the boss 5 by means of the lever bolt assembly 10. The yoke portion 8 carries a pawl member 11 by means of the pawl bolt assembly 12 passing through suitable openings in the yoke ends and the pawl. A flat spring member 13 secured to the side of arm 7 presses against the outer surface of the pawl 11.

A thrust block 14, having a dependent shank 15 extending into the drilled passage in boss 6, is supported by the boss, and secured thereto, as shown in Fig. 2, by means of a nut 16 engaging the threaded end of the shank 15. The block 14 is drilled to provide free passage for a threaded

eye-bolt 17, the head of which is secured in yoke 9 by means of bolt assembly 18. The free end of the eye-bolt 17 normally carries a power nut 19, flanged as at 20, to which a reversible ratchet wrench is secured by means of lock ring 21 and set screw 22. The power nut 19 is preferably spaced from the block 14 by means of washers 23.

The head 1 of the wrench base has an annular flange 24 extending inwardly about the lower end 10 of the opening therein, and is provided with an annular cover plate 25, which with the flange 24 forms a recess adapted to receive an anti-friction bearing or slip-ring 26, and a lubricant packing.

15 Means for adjusting the relation of the wrench base to the collar may be provided by base adjusting screws 27 and 28. Screw 27 may be disposed at the extreme end of the body portion of the base 1 while the screws 28 extend through ears 29 and which may be formed integral with the head 1.

That portion of the assembly which directly engages the work and is actuated to rotate is a collar member 30 having a ratchet toothed flange 31 at its upper end. The flange portion, as shown, has inwardly extending ears 32 carrying screws 33 for adjustment of the collar over a pipe end so that the toothed flange is level with the pawl 11 and may be engaged thereby. The collar member 30 also has an inwardly extending flange 34 at its lower end which provides a base for the collar and supports a series of rectangular dogs 35 set in slots 36 in the inner wall of the collar. As shown, three dog receiving slots are provided at spaced intervals on the collar wall. At a point adjacent the bottom of each slot, adjusting screws 37 having flanged heads 38 are threaded through openings in the collar wall. Each of the dogs 35 is formed with a T-slot 39, in its rear surface, to receive the flanged head 38 of a screw 37, and with teeth 40, on the front surface, to engage the work. In each slot 36, above each dog 35, is disposed a retainer block 41 secured to the rear wall of the slot by means of a retainer screw 42.

With specific reference to Figs. 3 and 4, in Fig. 3 is shown a perspective view of the wrench assembly in which the eye-bolt 17 has been removed from its connection in yoke 9, and a ratcheting handle 43 substituted therefor. This figure indicates the relation of the wrench to the work when used to break the connection between a safety valve 44 and the dome 45 of a tank car. In this figure, the numeral 46 designates the rim and cover of a manhole in the dome 45.

Fig. 4, as previously noted, is a sectional elevation of a portion of the wrench body, and ratchet wheel or collar 30. In this instance, the work consists of a pipe end 47 having a flared top portion. In order that the annular portion of the wrench body may be placed over the pipe and yet engage the pipe in the required manner, it is necessary to use a split anti-friction bearing ring 26a, of greater thickness. The ring has a smaller inside diameter than that of the ring 26 shown in Fig. 2, and although of a conventional split-ring type is otherwise similar to the ring 26 previously described.

In Fig. 5 is illustrated a two-section collar 30a in which the portions are joined by a combination butt and lap joint as w and x, and secured as by bolts y.

Fig. 6 shows a perspective view of a portion of the sectional ratchet wheel collar 30a providing a side view of the joint between sections.

In Fig. 7 is illustrated the head portion of a wrench base most suitable for use when it is desired to start a threaded joint in which one portion must be held stationary while the other is rotated, as previously set forth. Here, the head 48 of the base 1 is of substantially Stillson type. The head is an enlarged portion of the base having a ridged, lateral surface 49 disposed in angular relation to the center line of the body 2. From the main portion of the head 48 project parallel lugs 50 having concentric openings to provide passage for a resiliently-mounted, ridged clamping member 51, adjustable with relation to the surface 49 by means of the knurled nut 52.

The method of operating the wrench assembly described above is nearly self-evident from the description and by reference to Fig. 3 of the drawings. As illustrated, the head of the wrench body is placed over the protruding pipe end or valve casing, and the ratchet wheel collar applied. Normally the ears 32 will rest upon the pipe end and establish the position of the collar so that the ratchet teeth on flange 31 may be engaged by the pawl member 11. If the ratchet teeth and pawl are not in proper association the adjusting screws 33 may be used to elevate the collar to whatever height is required to properly position the ratchet teeth with relation to the pawl. With the collar in position on the pipe end, the screws 37 are turned to press the dogs 35 tightly against the pipe, the free end of the threaded eye-bolt 17 is passed through the thrust block 14 and the power nut threaded on the end. The eye-bolt is then secured in the yoke 9.

When the wrench has been thus set up, the longer portion of the arm 7 may be drawn toward the thrust block 14 by the movement of the eye-bolt through the block 14 and nut 19 by ratcheting movement of the wrench. The eccentric mounting of the arm 7 provides for a lever action, the bolt 10 acting as a fulcrum, to force the pawl 11 tangentially against the ratchet teeth on the collar 30 and with sufficient force to start even the most severely jammed threaded pipe connection. Once the pipe connection has been started, the eye-bolt may be disconnected from the arm 7, and the ratcheting handle 43

substituted in order to complete the unthreading of the pipe with greater speed.

It should be evident that the wrench body must be provided with a fixed lateral bearing surface in order that the thrust of the eye-bolt 17 or the handle 43 may be resisted. In Fig. 3, the wrench body bears against the manhole rim or cover. Likewise, as the application of force will tend to cause rotation of the wrench body about an axial point coincident with the fulcrum provided by the bolt assembly 10, the inner face of the annular head is brought into contact with the pipe end which is to be rotated. The slipping 10 15 20 25 30 35 40 45 50 55 60 65 ring 26 prevents binding at this point.

The use and operation of an assembly of which the elements are shown and described in connection with Figs. 5, 6 and 7 should be quite obvious. It is to be noted, however, that the parts are intended to be substantially interchangeable. For instance, the base shown in Fig. 7 may be used in conjunction with the collar illustrated in Figs. 1, 2 and 3, and likewise the sectional collar 30a may be used with the base shown in Fig. 7, if desired.

It is to be understood that the foregoing description and the drawings are only for the purpose of illustrating the invention set forth, which invention is to be limited only by the scope of the appended claims in which it is intended to claim all novelty inherent in the invention, as broadly as the prior art permits.

I claim:

1. A ratchet wrench assembly, comprising a wrench base, having an elongated body portion, and an annular head portion, a means mounted on said head to engage the work, a lever and pawl assembly pivotally mounted eccentrically of the body portion in spaced relation to said head portion, a thrust block member pivotally mounted eccentrically of the body portion, laterally opposite said pawl and lever mounting, in spaced relation to the end of said body, screw rod means, supported in said block, for imparting arcuate movement to said lever and pawl assembly, a peripherally ratchet-toothed collar, separate from the base, provided for fixed engagement with the work, and means carried by each of the base and collar elements for adjusting respectively their relation to each other and to the work.

2. A ratchet wrench assembly according to claim 1, in which said means mounted on said head portion is a slip ring rotatably secured in the head, concentrically thereof.

3. A ratchet wrench assembly according to claim 1, in which the screw rod means for imparting arcuate movement to said lever and pawl assembly comprises an eyebolt secured at one end to one end of the lever, said bolt having a threaded portion extended through and supported in the thrust block pivotally mounted on said base, and a ratchet wrench, including a power nut in threaded engagement with said eyebolt, said power nut engageable with and thrusting against said thrust block, when rotated, to draw the lever end toward said block.

GEORGE J. LANGMYHR.
